HYDRANT OR THE LIKE

Thomas C. Jester, Williamsport, Pa., assignor to Darling Valve & Manufacturing Company, Williamsport, Pa., a corporation of Pennsylvania

Filed Jan. 24, 1958, Ser. No. 49,384

Term of patent 14 years

(Cl. D91—3)

FIG. 1.

FIG. 2.

FIG. 3.

Figure 1 is a side elevational view of a hydrant showing my new design.

Figure 2 is an elevational view thereof as seen from the left of Figure 1.

Figure 3 is a top plan view thereof.

The sides of the hydrant not shown are plain. The dominant features of my design reside in the portions shown in full lines.

I claim:

The ornamental design for a hydrant or the like, as shown and described.
